UNITED STATES PATENT OFFICE.

EDWIN H. REED, OF HOLYOKE, MASSACHUSETTS.

PISTON.

SPECIFICATION forming part of Letters Patent No. 308,985, dated December 9, 1884.

Application filed March 1, 1884. (No model.)

To all whom it may concern.

Be it known that I, EDWIN H. REED, a citizen of the United States, residing at Holyoke, in the county of Hampden and State of Massachusetts, have invented an Improvement in Pistons, of which the following is a specification.

This invention relates to an improvement in a self-adjusting piston for steam, air, or liquid pumps, and for other purposes; and it consists in the means hereinafter described for self-adjustment to cylinder.

This invention is illustrated in the accompanying drawings, in which Figure 1 represents a central cross-section. Fig. 2 is an end view. Fig. 3 is a side view showing the cut in ring C.

Similar letters indicate corresponding parts. Letter A designates the hub of a piston cast or otherwise provided with a flange attached to piston-rod G.

C represents ring cut in three sections obliquely, as shown in Fig. 3.

D is an oblique and tapering wedge fitted between and forming part of sections of ring C, and extending centrally in an oblique line and resting on cone or conical wedge E, which is fitted loosely to hub A and chambered out for spiral spring F, as shown in Fig. 1.

B is a follower fitted to hub A, and passes over piston-rod G and secured to place by nut H or otherwise. This piston works substantially as follows: When any wear of either cyl-

inder or piston is to be compensated for, the spiral spring F presses cone E over hub A, 35 thereby pushing outward tapering wedges D, which carry with them sections of ring C to cylinder, the whole being clamped between flanges B and corresponding flange on hub A, which is attached to piston-rod G by nut H, 40 or other suitable means.

What I claim as new, and desire to secure by Letters Patent, is—

Ring C, cut in three or more sections obliquely and beveled, and wedge D, which is 45 also cut obliquely and tapering and fitted between sections of ring C, so as to bear on cylinder on same circle as sections of ring C, extending centrally and resting on conical wedge or cone E, which is fitted loosely over hub A, 50 and held in position by spiral spring F, which presses cone E over hub A, and adjusts wedges D and ring C to size of cylinder in which the piston is used, so that any wear of either cylinder or piston will be readily compensated for by 55 spiral spring F pressing cone E over hub A, thereby pushing outward tapering wedges D, which carry with them sections C to cylinder, thereby leaving no open joints, and at the same time taking up the smallest wear and 60 adjusting itself evenly on all sides without any sudden or undue friction.

EDWIN H. REED.
